QUICK DETACHABLE LAMP AND SOCKET

Filed March 6, 1934 2 Sheets-Sheet 2

Fig. 4.

Fig. 5.

A technical line drawing of a mechanical assembly. It features a base 19 with a stepped profile. A vertical plate 18 is positioned on the left side. A horizontal plate 16 is centered, supported by a central vertical post. A rectangular cutout 20 is located in the base 19, aligned with the central vertical post. A small part 15 is attached to the right side of the central vertical post. A circular feature 21 is located on the right side of the base 19, just above the cutout 20.

QUICK-DETACHABLE LAMP AND SOCKET

Nicholas Louis Guljas, Jr., South Bend, Ind.

Application March 6, 1934, Serial No. 714,342

1 Claim. (Cl. 173—350)

This invention appertains to new and useful improvements in quick-detachable connectors for lamps, and more particularly to the combination of a lamp base and socket structure therefor.

5 Another important object of the present invention is to provide a combination lamp and lamp socket of the quick-detachable type wherein the parts are durably constructed and not susceptible to the development of ready defects.

10 Other important objects and advantages of the invention will become apparent to the reader of the following specification.

In the drawings:—

Figure 1 represents a vertical sectional view 15 through the socket, fragmentarily showing the electrical connector and the lamp base in side elevation.

Figure 2 represents a vertical sectional view 20 through the socket structure, showing a connector and lamp in side elevation.

Figure 3 represents a transverse sectional view taken substantially on line 3—3 of Figure 1.

Figure 4 represents a vertical sectional view 25 through the connector, fragmentarily showing the lamp in side elevation.

Figure 5 represents a vertical fragmentary sectional view taken substantially on line 5—5 of Figure 4.

Figure 6 represents a perspective view of the 30 spring contacts and carrier frame therefor.

Figure 7 represents a fragmentary sectional view through the base portion of the lamp.

Referring to the drawings wherein like numerals designate like parts, it can be seen in 35 Figure 1 that numeral 5 represents a di-electric shell provided with external threads at one end and against which the cap 6 is engageable. This cap 6 is flanged circumferentially and with this is engaged the internally threaded and flanged 40 ring 7 which can be fed on to the threaded end portion of the shell 5 for suitably securing the cap 6 to the shell 5.

The opposite end of the shell 5 is flanged inwardly, as at 8, while the intermediate portion 45 of this shell 5 is offset inwardly to define a shoulder 9 upon which the di-electric core 10 can engage, while the cap 6 engages against the opposite end thereof to firmly clamp the core 10 within the shell.

50 The cap 6 is provided with a neck 11 and an internally threaded bushing 12. A set screw 13 is disposed through the neck 11 and into the bushing 12 and obviously, a suitable conductor cable can be secured therein.

55 The bottom side of the core 10 is provided

with a polygonal-shaped boss 14 which is received by the rectangular shaped opening 15 of the frame 16, which frame is provided with a pair of upstanding leg members 17—18 and a pair of depending spring arms 19—19, each having its free end bent outwardly, these outwardly bent, free ends being diverged in the manner shown in Figure 6, while slightly inwardly of each of these outwardly bent end portions is a curved or grooved portion 20 which receives the circumferentially extending rib 21 on the metallic jacket 22 of the lamp base, the lamp bulb being denoted by numeral 23.

The base of the lamp has a core 24, as shown in Figure 7, of di-electric material, the end of 15 which is provided with a contact 25 connected by the usual conductor 26 extending through the base. Obviously, this conductor 26 connects to one side of the filament (not shown), while the other end of the filament is connected by 20 the conductor 27 to the metallic jacket 22.

Numeral 28 represents a contact which is of 25 spring material and substantially U-shaped, as shown in Figure 4, one leg portion of which is provided with the extension 29 and the transversely curved head portion 30 adjacent the cam element 31. Numeral 32 represents a binding post at one side of the core 10, while extending from this is the spring arm 33 terminating in an arcuate-shaped head 34 and located in opposed relation with respect to the head 30.

The cam member 31 is interposed between the heads 30—34 and is carried by a shaft 35 journaled into the core 10 and provided with a 35 knob 36.

The legs 17—18 of the frame 16 extend upwardly into the core 10, the leg 18 being connected to a binding post 38 by a strap 39. A bolt 40 extends through the lower end of this strap 39 and through the members 17—18 and is 40 equipped with a nut 41 whereby the sections of the core 10 will be retained together.

Obviously, the lamp base can be pushed up into the shell 5 and will readily snap between the depending spring legs 19—19 and when the 45 cam 31 which forms a connector bridge in itself is in the position shown in Figure 4, current will be supplied by way of a suitable conductor (not shown) to the filaments of the lamp.

While the foregoing specification sets forth the 50 invention in specific terms, it is to be understood that numerous changes in the shape, size and materials may be resorted to without departing from the spirit and scope of the invention as 55 claimed hereinafter.

Having described the invention, what is claimed as new is:

An electric switch socket structure comprising a hollow dielectric body divided into a pair of 5 sections, a switch in the body including a pair of spring contacts and a rotary contactor operative against said contacts, a knob for actuating the contactor, said body provided with a depending boss, a frame provided with a pair 10 of upstanding leg members having openings in their end portions, said frame having an opening therein through which the frame snugly receives the boss, a pair of lamp base engaging and retaining arms depending from the frame, a

conductor extending from one of the switch contacts, a U shaped spring contact on the lower end of the conductor with one leg portion thereof extending through the bottom of the boss to engage with the contact of a lamp held between the spring arms, said upstanding leg members being disposed along opposite sides of the body, said body having a bore therethrough through which the openings of the leg members are alignable, a bolt for disposition through the openings of the legs and the bore of the body, for holding the sections of the dielectric body and retaining arms frame together. 5 10
